United States Patent Office.

ROBERT GRACEY, OF PITTSBURG, PENNSYLVANIA.

Letters Patent No. 72,288, dated December 17, 1867.

IMPROVED BOLT-HEADING MACHINE.

The Schedule referred to in these Letters Patent and making part of the same.

TO ALL WHOM IT MAY CONCERN:

Be it known that I, ROBERT GRACEY, of Pittsburg, in the county of Allegheny, and State of Pennsylvania, have invented a new and improved Machine for Making and Heading Bolts, Rivets, and Spikes; and I do hereby declare that the following is a full, clear, and exact description thereof, reference being had to the accompanying drawings, and to the letters of reference marked thereon, in which—

Figure 1 is a side elevation of the machine, some of the parts being shown in section.

Figure 2 is a plan view, the levers C', E and E' being removed.

Figure 3 is a cross-section.

Figure 4 is a face view of the stationary heading and griping-dies; and

Figure 5 is a similar view of the movable dies.

Like letters refer to the same parts in all the figures.

A is the frame, which supports the operative part of the machine. B is the main shaft, by the rotary motion of which all the moving parts of the machine are operated. C is a cam on the main shaft to operate the heading-lever. C', D, and D' are cams on the same main shaft to operate the levers E and E', which move the heading and griping-dies d' and e'. F is a toggle-joint lever, which gives motion to the heading-hammer f, being connected to lever C' by a stem, F', and operated by said lever. Said toggle-lever F operates between a stationary head, g, and a working head, g', which carries the heading-hammer, and moves between two bars, a a, of the frame, and under a cross-plate attached to said bars a a by means of screws. The stationary head g is confined between said bars a a by a cap-plate and a set-screw in said cap, and is adjustable, to regulate the distance between the heading-hammer and the heading-die, by means of a temper-screw, i. d and d' are the heading-dies, d being stationary, and d' movable. e and e' are the cutters, e being in the stationary griping-die, and e' in the moving-die, to cut the bolt the required length. The length of the bolt may be varied by changing the griping-dies. The movable heading and griping-dies are operated by the toggle-joint levers G and G', which are connected to the levers E and E' by the toggle-stems j j'. The heading and griping-dies move back and forth together, except that the griping-die moves forward slightly in advance of the heading-die, so that it grasps the bolt-rod before the heading-dies are fairly closed upon it. The recesses in the heading-dies to grasp and enclose the bolt-rod are completely semicircular, and are large enough to allow for slight variations in the size of the iron, and yet always close together around it; but said recesses in the griping-dies are a little less than semicircular, as shown at o, so that the dies will not quite close around the rod, but will stand a little open when the rod is gripped by them. The object of having the griping-dies close upon the rod, a little in advance of the heading-die, is to leave the iron free to move slightly between the heading-dies as the cutters sever it; and this variation in the movement of the heading and griping-dies is regulated by the adjustment of the cams D and D' on the main shaft B. L is a lever, turning on its fulcrum l, and held against a collar, n, on the cam D, by a spring, n'. This lever is actuated, suddenly, by a knocker, k, on said collar, just as the dies open, and throws forward a small piston, k', working through one of the stationary dies, to throw out the finished bolt if it should be inclined to stick. In like manner a stationary stake, s, straddled by a slot in one of the movable dies, detaches the bolt from the moving-dies as they recede from it. The cam C is made in two sections, m and m', m being stationary on the shaft, and m' removable by means of screws, so that it may be changed, and a section of different form substituted to vary the throw of the heading-hammer, and thus adjust the machine to form a head with more or less metal in it. P is a hollow cylindrical post, (shown in section,) containing a rubber spring, p, and an iron piston or follower, p', the head of which, covered with leather or some similar substance, receives the weight W as the lever falls, and causes it immediately to rebound, and thus remove the hammer from the hot iron the instant it has made its blow and formed the head of the bolt; and before said weight will again descend, the cam C will have moved so far as to meet it and arrest its descent. Q is a rubber upon the lever-bar C', on which the cam C directly acts. It projects far enough below the lever-bar to allow it to drop suddenly when the heading-hammer makes its stroke. The weight W must be sufficient to cause the heading-hammer to do its work, and may be detached, and a heavier or lighter one may be substituted, according to the size of the bolt to be headed.

When the dies are apart, the bolt-rod, with its extreme end heated to a welding-heat, is inserted between them, so that its heated end will come in contact with the heading-hammer. The dies then close upon it in

the order before stated, the cutters sever it, and instantly afterwards the hammer makes its blow, forming the head. The dies then separate, and the finished bolt drops down from between them. The hammer in receding does not pass out from between the dies. By removing the cutters from the dies, bolts of any desired length may be headed on this machine.

It is manifest that by changing the dies, spikes and rivets may be made and headed on this machine without any other modification.

It will be observed that neither the movable dies nor the heading-hammer are controlled by a positive movement, but the motion of each is determined by the mass of metal operated upon, so that any accidental increase in the mass of said metal will not subject the machine to any unusual strain.

Having thus fully described my machine and its mode of operation, what I claim as my invention, and desire to secure by Letters Patent, is—

1. The combination of the cam C, the weighted drop-lever C', the toggle F, and the heading-hammer, constructed, arranged, and operating together substantially as described.
2. The combination of the cams D and D', the levers E and E', the toggles G and G', and the movable heading and gripping-dies, constructed, arranged, and operating together substantially as described.
3. In combination with the heading-hammer, the toggle F, the drop-lever C', and cam C, I claim an elastic post, stud, or other elastic bearing, to arrest the descent of the drop-lever, and cause it instantly to rebound and remove the hammer from the heated iron, substantially as shown and described.
4. In combination with the heading and gripping-dies, I claim the piston-k and stakes, arranged and operating as described, to detach the finished bolt from the dies.

ROBERT GRACEY.
